UNITED STATES PATENT OFFICE.

GOTHARD LOWENSTEIN, OF BROOKLYN, NEW YORK.

DETACHABLE-LENS MOUNTING.

Application filed September 2, 1920. Serial No. 407,661.

To all whom it may concern:

Be it known that I, GOTTHARD LOWENSTEIN, a citizen of the United States, residing in the borough of Brooklyn, city of New York, 5 county of Kings, and State of New York, have invented certain new and useful Improvements in Detachable-Lens Mountings, of which the following is a full, clear, and exact description, reference being had to the 10 accompanying drawings, forming a part of this specification.

This invention relates to lens mountings, and more particularly to detachable lens mountings, arranged so that a lens is readily 15 detachable from the frame work normally supporting same, without the necessity of using any tools, and can also just as readily be replaced.

Arrangements and constructions of lens 20 mountings whereby a lens may be readily detached from or attached to the frame are not new in the broad sense of the word; devices of this character having been described and claimed by me in two patents for lens 25 mountings, one bearing No. 914,149, patented March 2, 1909, and the other bearing No. 1,005,248, patented October 10, 1911.

The primary object of the present invention is to provide an improved construction 30 of detachable lens mounting for eyeglasses and spectacles, whereby an absolutely positive and lasting locking action is assured between the lens head and the lens holding stud, and whereby a perfectly rigid connection 35 is obtained.

Another object of this invention is to provide a spring controlled detachable lens mounting the construction of which is such that while sufficient room is allowed for effective play of the spring, the spring itself 40 can be located entirely between the bridge piece and the lens head, interlocking with the lens head near or at its edge portion, without projecting on or interfering with 45 the surface of the lens.

A still further object of this invention is to provide an improved construction of detachable lens mounting whereby not only is a highly efficient and rigid locking action 50 obtained, but the number of parts employed is reduced to a minimum and the cost of manufacture considerably lessened.

With these and other objects in view, as 55 will more fully appear as the description proceeds, this invention consists in certain constructions and arrangements of parts as

will be hereinafter fully described and claimed in the appended claims.

In eyeglasses of ordinary construction, the lens holding studs and the bridge are 60 usually made separately and connected together by means of screws or other convenient means. One of the novel points of my improved construction is that the bridge and the lens holding studs can be blanked 65 and formed together from a sufficiently rigid piece of sheet metal or wire. Another novel point, which bears more particularly on the class of devices to which this invention refers, is that the spring latch which 70 is used in order to provide the locking action between the lens head and the stud, is also blanked and formed integral with the stud and bridge, from the same piece of sheet metal or wire of suitable thickness. 75

The simplified construction of eyeglass frame resulting from my invention can be embodied in connection with a great number of styles of lens mountings, and is suitable for use both in connection with the 80 ordinary lens mounting, and in connection with the so called finger piece style of lens mounting.

In the annexed drawings, I illustrate two ways of carrying my invention into practice, and in the same:

Fig. 1 is a detail side view in elevation of a portion of eyeglasses, showing a lens head detachably connected to its stud;

Figs. 2 and 3 are respectively a detail 90 side sectional view in elevation and a detail plan view of the lens and lens head used in the construction shown in Fig. 1;

Figs. 4 and 5 are respectively a detail side view in elevation and a plan view of the 95 stud integral with the spring latch and bridge also used in the construction shown in Fig. 1;

Fig. 6 is an enlarged detail side view in elevation, partly sectioned, of a device similar to the one shown in Fig. 1, showing the way of connecting the lens head to the stud;

Fig. 7 is a detail side view in elevation, partly sectioned, of a similar device, in 105 which the spring latch acts in a direction opposite to that of the spring latch shown in the other drawings; and

Fig. 8 is a detail plan view of a locking arrangement built along the lines of the one 110 shown in Fig. 7, where however the spring moves on a plane parallel to the surface of

the lens instead of being arranged crosswise to the same.

Similar characters of reference indicate corresponding parts in the various figures.

5 Referring to the drawings, 10 designates a lens provided with a lens head 11, which is mounted on said lens in any suitable manner, for instance by means of a screw 12. Said lens head is formed with an upwardly 10 projecting lug 13, and a downwardly projecting lug 14, respectively provided with slots 15, 16. 17 designates the bridge of an eyeglass or spectacle frame, which is made out of sheet metal or wire, integral 15 with a stud 18, and integral also with a latch 19, acting as a spring on account of its being obtained by producing a long slot 20 in the body of said stud. Said spring latch 19 is provided with a hook formed 20 portion 21, which is adapted to be inserted through slot 15 and to interlock with lug 13 of lens head 11.

The lower part of the stud is formed with a nose 22, provided with a notch 23. Said nose 22 is adapted to be inserted through slot 16, thereby causing said notch 23 to interlock with lug 14 of lens head 11.

The manner of connecting the two parts together is clearly illustrated in Fig. 6. 30 From the same it appears that in order to attach the lens to the stud, it is sufficient to insert nose 22 through slot 16 causing notch 23 to interlock with lug 14; then using lug 14 as a fulcrum, to cause hook formed part 35 21 of spring 19 to pass through slot 15, causing the depression of said spring. As soon as part 21 has passed slot 15, the spring will spread out, and part 21, interlocking with lug 13, will rigidly secure the lens to 40 the stud. 24 designates a hole which may be provided for mounting a fulcrum pin, when my improved construction is used in connection with the finger piece style of lens mounting. In this figure spring 19 is 45 shown attached at 19' to the stud instead of being formed in one piece with the same. Such a construction may be adopted when the material of which the stud is made is not sufficiently resilient, or when an absolutely effective tempered spring is wanted. 50

In order to detach the lens from the stud, it is sufficient to press down spring latch 19 with the thumb nail against part 21, until said part 21 clearing slot 15, the operation 55 can be reversed.

In Fig. 7, I illustrate a modified form of lens mounting in which the stud 25 is provided with a spring latch 26 having a hook formed portion 27 adapted to be inserted 60 through an opening 28 and to interlock with lug 29 of lens head 30. In the present in-

stance, however, the hook formed portion 27 is directed downwardly, and may be disengaged by lifting the same with the thumb nail, instead of pressing down as explained 65 in connection with the style of device shown in the previous drawings.

In Fig. 8 I show a style of locking arrangement which is built along the same lines as the ones previously described, with 70 the difference that lens head 31 is provided with lugs 32, 33 extending one on each side along the edge of the lens instead of crosswise to the same; the stud 34, provided with hook portion 35 and with spring 36 being 75 similarly arranged in a plane parallel to the surface of the lens. No particular advantage is claimed for this form of construction, which is equally effective as the ones previously shown, and which is illustrated 80 only as an example of optional alternative construction.

From the foregoing, it is seen that I provide a simple and novel construction of detachable lens mounting, whereby a strong 85 and positive spring locking action may be obtained, and whereby the rigidity of the entire construction is assured through the employment of a minimum number of parts.

I claim:

1. In a device of the class described, the combination of a lens, a lens head mounted on the same provided with two slots, and a lens holding stud formed in one piece with a notched member adapted to interlock with 95 one of said slots, and with a spring acting member adapted to interlock with the other slot.

2. In a device of the class described, the combination of a lens, a lens head mounted on the same provided with slots, and a lens holding stud adapted to interlock with said lens head, said stud being formed in one piece with a notched portion adapted to engage one of said slots, and being furthermore provided with an elongated slot causing said stud to be formed into a body portion and a spring acting latch adapted to interlock with the remaining slot in said lens head. 100

3. In a device of the class described, the combination of a lens, a lens holding stud provided with an elongated slot causing said stud to be formed into a body portion and a spring acting latch, and a lens head mounted on said lens adapted to interlock with said body portion and having a slot adapted to interlock with said spring acting latch. 110

GOTHARD LOWENSTEIN.
